to disclose how to make and use the same. The invention relates to a record player which may be manually placed on a record driver for transcription, and it aims to provide a relatively simple and inexpensive machine for use primarily in small stores, restaurants and the like, the proprietors of which do not feel justified in installing an expensive automatic record player such as those commonly known as "juke boxes." The construction of the invention is such that the records are accessibly confined for placing on and removal from the record driver, yet cannot be removed from the confining means by any unauthorized person. Thus, without danger of anyone stealing or breaking records, the customers may play desired selections, for which payment may be collected, and it is preferable to collect this payment by having the motor of the record driver coin-controlled.

Figure 1 of the accompanying drawings is a perspective view showing one form of the invention.

Fig. 2 is a front elevation partly broken away and in section.

Fig. 3 is an end elevation partly broken away and in section.

Fig. 4 is a top plan view showing a different form of construction.

Fig. 5 is a front elevation of the device shown in Fig. 4.

Fig. 6 is a side elevation of the device illustrated in Figs. 4 and 5.

In the drawings above briefly described, preferences have been illustrated, and while the construction disclosed will be rather specifically described, attention is invited to the possibility of making numerous variations within the scope of the invention as claimed.

In the form of construction shown in Figs. 1 to 3, a horizontal rectangular body or casing 10 is shown, having suitable supporting legs 11. Within this casing, is a false bottom 12 preferably having a depressed portion 13 at one of its ends. Two longitudinal wall members 14 project upwardly from the false bottom 12 in inwardly spaced parallel relation with the side walls 15 of the casing 10, said members 14 being secured at their ends to the casing end walls 16. Preferably, longitudinal horizontal panels 17 extend laterally from the upper edges of the wall members 14 to the casing side walls 15.

The side members 14, the portions of the casing ends 16 extending between said members 14, and the bottom 12, are cooperable in forming an upwardly open elongated channel 18. This

channel is shallow vertically, its height being very much less than the diameter of the disk records used in the cabinet. In one end of this channel, a record player having the conventional turntable 19 or other record driver and the usual arm 20 of the transcribing means, are mounted, and the remainder of the flat and unobstructed bottom of the channel 18 provides a storage space for a plurality of records 21, any of which may be 5 manually placed upon the driver 19 for transcription. The motor of this driver is preferably coin-controlled by appropriate means including a conventional coin-injecting slide 22 (Fig. 1). Removal of any of the records 21 from the channel 18, is prevented by two top panels 23 which may well be formed from glass or other transparent sheet or plate-like material, suitably held in a frame 24 secured to the casing 10. The inner edge portions of the top panels 23 project 10 inwardly beyond the longitudinal wall members 14 and overlie the records 21, said top panels being spaced apart sufficiently to give ample access by hand to said records 21 and to the record driver 19 to permit any record to be placed upon 15 said driver. However, the space between the inner edges of the panels 23 is insufficient to permit the removal of any of the records, even when a record is shifted against one of the wall members 14 and tilted, as seen in Fig. 3. 20 It is to be noted from this view that the distances between the inner edges of the top members and the diagonally opposite lower corners of the channel 18 are less than the diameters of the disk records used in the cabinet. Thus, while 25 any selected record may be played, theft of records is prevented and there is no danger of dropping any of them on the floor and breaking them.

The portion of the bottom 12 which supports 30 the records is preferably covered with felt or the like as shown at 25, and this covering may well extend also to other parts, if desired, to give an attractive interior appearance.

Any suitable provision may be made to permit 35 an authorized person to remove and insert records. For illustrative purposes, one of the end walls 16 of the casing 10 is shown as provided with a removable section 16' for this purpose, and said section will of course be normally locked in place by any suitable means.

At 26, we have illustrated a screened sound outlet in the front of the box 10, through which the sound waves are emitted from the usual speaker unit of the transcribing mechanism. 45 However, as most of the top of the channel 18 is

4 Claims. (Cl. 274—2)

1

The invention relates to a record player in which any selected record may be manually placed on a record driver for transcription, and it aims to provide a relatively simple and inexpensive machine for use primarily in small stores, restaurants and the like, the proprietors of which do not feel justified in installing an expensive automatic record player such as those commonly known as "juke boxes." The construction of the invention is such that the records are accessibly confined for placing on and removal from the record driver, yet cannot be removed from the confining means by any unauthorized person. Thus, without danger of anyone stealing or breaking records, the customers may play desired selections, for which payment may be collected, and it is preferable to collect this payment by having the motor of the record driver coin-controlled.

Figure 1 of the accompanying drawings is a perspective view showing one form of the invention.

Fig. 2 is a front elevation partly broken away and in section.

Fig. 3 is an end elevation partly broken away and in section.

Fig. 4 is a top plan view showing a different form of construction.

Fig. 5 is a front elevation of the device shown in Fig. 4.

Fig. 6 is a side elevation of the device illustrated in Figs. 4 and 5.

In the drawings above briefly described, preferences have been illustrated, and while the construction disclosed will be rather specifically described, attention is invited to the possibility of making numerous variations within the scope of the invention as claimed.

In the form of construction shown in Figs. 1 to 3, a horizontal rectangular body or casing 10 is shown, having suitable supporting legs 11. Within this casing, is a false bottom 12 preferably having a depressed portion 13 at one of its ends. Two longitudinal wall members 14 project upwardly from the false bottom 12 in inwardly spaced parallel relation with the side walls 15 of the casing 10, said members 14 being secured at their ends to the casing end walls 16. Preferably, longitudinal horizontal panels 17 extend laterally from the upper edges of the wall members 14 to the casing side walls 15.

The side members 14, the portions of the casing ends 16 extending between said members 14, and the bottom 12, are cooperable in forming an upwardly open elongated channel 18. This

open, it would of course be possible to have the sound waves emitted into this channel instead of having a special outlet in the casing.

In Figs. 4, 5 and 6, a casing 27 is shown, said casing having forwardly converging side walls 28, a rear wall 29, and a front wall 30. Within the casing is a false bottom 31, and over the front portion of this false bottom, the record driver 32 and arm 33 are mounted. The rear portion of this bottom serves to support the records 34. The 10 casing is provided with a transparent top 35 and access to the records and record driver is given by means of two openings 36 in the side walls 28. These openings are of such size that a person may insert his forearms through them when 15 standing in front of the machine, permitting movement of records to and from the driver 32. The openings 36, however, are sufficiently small to prohibit removal of any record through them.

The records, in both forms of the invention, are 20 preferably given identifying numbers and the machine will conspicuously display a catalogue of the records, identifying them not only by name but by number, permitting easy location of any selected record. The record may be easily placed 25 on the record driver by hand and the tone-arm moved to starting position by hand, and while rotation of said record driver may be controlled in any suitable way, it is preferable to use a coin-controlled mechanism for this purpose, and said mechanism may be such as to rotate said driver sufficiently long to play one or more records, as 30 desired.

From the foregoing, taken in connection with the accompanying drawings, it will be seen that 35 novel and advantageous provision has been made for attaining the desired end, and while preferences have been illustrated, attention is again invited to the possibility of making variations within the scope of the invention as claimed.

We claim:

1. A record player cabinet to accessibly confine a plurality of sound disk records and a record driver to which any of the records may be manually applied for playing, the cabinet being for use in a public place where members of the public are permitted to selectively play any of the records but are prevented from removing any of them from the cabinet, said cabinet comprising a casing having an unobstructed bottom member 50 on which a plurality of disk records may be directly and flat-wise supported adjacent a record driver to which records may be applied by hand, side members and end members, said bottom, side and end members all cooperating in forming an elongated upwardly open channel, said casing also including longitudinal top members projecting inwardly from said side members with the inner edges of the top members spaced apart sufficiently to give access by hand to records and 55 said driver within said channel but insufficiently to permit removal of any confined record through the space between said members.

2. The structure of claim 1 in which the distance between the inner edges of said top mem- 60

bers and the diagonally opposite lower corners of said elongated channel is less than the diameters of the disk records to be used in the cabinet, whereby such confined records may not be tilted to remove them from the casing through the space between said top members.

3. The structure of claim 2 in which said top members are transparent plates through which records and record driver in said channel may be seen.

4. A record player cabinet to accessibly confine a plurality of sound disk records and a record driver to which any of the records may be manually applied for playing, the cabinet being for use in a public place where members of the public are permitted to selectively play any of the records but are prevented from removing any of them from the cabinet, said cabinet comprising a horizontal, rectangular casing including side members, end members and bottom members all cooperable in forming an elongated upwardly open channel in which may be positioned a plurality of disk records and a record driver to which records may be selectively applied by hand for playing, said channel being shallow vertically and of less depth than the diameter of a disk record but having a horizontal width greater than the diameter of a disk record, the bottom of said channel being flat and unobstructed to permit records to be directly supported flat-wise thereon, disk records being shiftable by hand longitudinally in the channel for application to a driver, and horizontal transparent top members on said casing and extending longitudinally thereof with their opposed inner edges spaced apart over said channel, the spacing of said top members being less than the diameter of a record but sufficient to give access by hand to records and a driver in the channel, the distance between the spaced inner edges of said top members and the diagonally opposite lower corners of said elongated channel being less than the diameters of disk records to be used in the casing, whereby records confined in said channel may not be removed from the latter through the space between said top members by tilting records from the horizontal.
